UNITED STATES PATENT OFFICE.

CHARLES H. COOLEY, OF HARTFORD, CONNECTICUT, ASSIGNOR TO THE PRATT & WHITNEY COMPANY, OF SAME PLACE.

VALVE-OPERATING MECHANISM FOR GRAIN-SCALES.

SPECIFICATION forming part of Letters Patent No. 402,510, dated April 30, 1889.

Application filed November 12, 1888. Serial No. 290,635. (No model.)

To all whom it may concern:

Be it known that I, CHARLES H. COOLEY, a citizen of the United States, residing at Hartford, in the county of Hartford and State of Connecticut, have invented certain new and useful Improvements in Valve-Operating Mechanism for Grain-Scales, of which the following is a specification.

This invention is in the nature of an improvement on the mechanism for a similar purpose which is described in the United States Patent No. 302,136, granted to John W. Hill July 15, 1884.

The object of my present improvements is to furnish means operating in connection with the "toes K²" of said patent for positively limiting the first downward movement of the grain-bucket, this movement being due to the weight of the major part of the load of grain in said bucket.

In the drawings accompanying and forming a part of this specification, Figure 1 is a side elevation of those parts of the grain-scale shown in said prior patent which comprise my improvements. Figs. 2 and 3 are similar views illustrating the operation of the devices. Fig. 4 is a rear view of the toe K² and certain other details. Fig. 5 shows a modified form and arrangement of the said toe K² and the hook carried thereon.

Similar characters designate like parts in all the figures.

The "grain-spout G" of said patent is shown herein chiefly by dotted lines, being broken away the better to show the operative details. The following several parts herein shown are supposed to be substantially the same as the corresponding parts similarly designated in said prior patent, to wit: The scale-beam B, the valve-shaft J, the shaft-bearings G', the valves H and H', the valve-supporting arms h and h' and their clutches, (not herein shown,) the gravity-pawl L, pivot l, and stop b, the toes K', operated by said pawl L, and the cam-stop M, which is attached to beam B by screws m.

The toe K², which I prefer to call the "stop-cam," is similar in its construction and functions to the same part in Hill's said patent; but I attach to said cam a hook or stop, 4, for positively limiting the downward motion of

cam-stop M prior to the closing of valve H. This hook is pivotally connected to the cam at about the point 3, and has a projecting end, 5, on which the stop M strikes. The positions of the stop M and cam K² during the time the grain-bucket is receiving the major part of its load are shown in Fig. 1. When the main weight is overbalanced and the beam B descends, the stop M goes directly down onto hook 5, thereby stopping the downward movement of the beam at a point where the cam K² can swing back from its position in Fig. 1 to that in Fig. 2, thus closing the main valve H. This movement carries the hook 5 from under cam M, so that at the next downward impulse of the beam (when the supplemental weight is lifted) the cam-stop M clears said hook and descends to its lowest limit, in Fig. 3. On the rising of the beam the pawl L lifts the toe K' and swings forward cam K², and again carries stop M upward to its position in Fig. 1, the hook 4 swinging back (not shown) in the meantime to permit such movement of said stop, and then falling forward with the end 5 thereof underneath the stop.

The form and arrangement of the hook 4 may be varied from that shown in Figs. 1 to 4 without altering the essential character thereof. One such modification is shown in Fig. 5, in which the said hook 4 is carried on a rigid arm, 6, depending from said cam K². In this case the hook is or may be in the nature of an ordinary gravity-pawl, and is limited in its forward movement by the stop 7 on said arm 6. A spring (not shown) may be employed to hold said pawl 4 normally against the stop 7.

It will be remembered by those practically acquainted with this class of grain-scales that the first downward movement of the beam begins at the moment the increasing load of grain overbalances the main weight, and that since the flow of grain continues said load is constantly augmenting as the bucket and beam descend. Consequently it is evident the said motion of the beam is constantly accelerating, so that the load is acting when the beam takes up the supplemental weight, both by its rear weight and by its momentum; and it happens often in practice that these two forces combined will lift the supplemental weight prematurely sufficiently to allow the

stop M to pass under the second notch K of said cam K². This allows the valve H' to close too early, thereby cutting off the grain-supply and thus stopping the operation of the machine. By my improvements, however, the said effects of the load's momentum added to its weight are effectually overcome. The result is that not only is the aforesaid uncertainty obviated, but the supplemental weight may be largely reduced relatively, the flow of grain be increased, and in general a higher efficiency of the machine attained.

Having thus described my invention, I claim—

15 1. In a grain-scale, the combination, with a

stop-cam controlling the closing of the valves, of a cam-stop carried on the scale-beam and acting on said cam, and a stop connected to said cam and located to limit the first downward movement of the beam, all organized 20 and coacting substantially as described.

2. The combination of the scale-beam having stop M, the valve-shaft carrying cam K², and the hook 4, movably connected to said cam and having the stop-face 5, substantially 25 as described.

CHARLES H. COOLEY.
